UNITED STATES PATENT OFFICE.

AUGUSTUS H. HEISEY, OF PITTSBURG, PENNSYLVANIA.

DESIGN FOR GLASSWARE.

SPECIFICATION forming part of Design No. 12,371, dated July 26, 1881.

Application filed June 18, 1881. Term of patent 7 years.

To all whom it may concern:

Be it known that I, AUGUSTUS H. HEISEY, of Pittsburgh, in the county of Allegheny and State of Pennsylvania, have invented a new and useful Improvement in Designs for Glassware; and I do hereby declare the following to be a full, clear, and exact description thereof.

My improved design for glass dishes consists of a square, rectangular, or other polygonal shape, with the corners escutcheoned with clear shell-patterns and the intermediate portion frosted or obscured.

To illustrate I have shown this design in the accompanying drawings applied, in Figure 1, to a nappy, and in Fig. 2 to a salver.

In Fig. 1, *a* indicates the clear shell-figures on the corners of the rectangular bowl, and *b* the intermediate frosted part. The frost-work may be of any known character, the term being used to cover generally an obscured or partially-obscured surface, whether produced by a roughened mold, or by grinding, or by acid.

In Fig. 2, *a* also indicates the clear shell-

figures on the corners of the square salver, and *b* the frosted surface.

If desired, clear figures *c* may appear in the frosted body, but not enough to destroy its general character.

The design is carried out in the foot or stem by shells *a'*, frosted part *b'*, and ornaments *c'*.

This design is applicable to other articles of glassware beside those shown, and is handsome in appearance.

What I claim as my new and useful design for glassware is—

The polygonal shape with corners escutcheoned with clear shell-patterns and intermediate frosted patterns, substantially as described and shown.

In testimony whereof I have hereunto set my hand.

AUGUSTUS H. HEISEY.
